UNITED STATES PATENT OFFICE.

SIMON S. TAINTER, OF DIXFIELD, MAINE.

MACHINE FOR ASSEMBLING CLOTHESPINS.

Application filed April 13, 1926. Serial No. 101,835.

A well-known form of clothes-pin comprises two clamping members generally made of wood and a spring member, the spring member having a coil portion which lies between the two clamping members intermediate their ends, the ends of said spring having portions which engage the clamping members to secure the spring thereto, all so arranged that said spring will normally hold the jaw portions of the clamping members in yielding engagement with each other, the other ends of said clamping members serving as handles which are normally spread apart when the clamping jaws are closed and which may be pressed toward each other by the user in order to open the jaw members. The object of the present invention is to provide a machine for assembling the clamping members and spring together.

The invention will be fully understood from the following description when taken in connection with the accompanying drawings and the novel features thereof will be pointed out and clearly defined in the claims at the close of this specification.

In the drawings:

Fig. 1 is a front elevation of a substantially complete machine embodying the invention.

Fig. 2 is a side elevation, partly broken away.

Fig. 3 is a plan view of the machine shown in Fig. 1, the feeding means for the clamping members being omitted.

Fig. 4 is an enlarged section on line 4—4, Fig. 1.

Fig. 5 is a perspective view of a completed and assembled clothes pin.

Fig. 6 is a perspective view of the spring member before it is assembled with the clamping members.

Figs. 7, 8, 9 and 10 are diagrams illustrating successive positions of the work and certain parts of the machine during the cycle of operations.

Fig. 11 is a section on line 11 of Fig. 9.

Referring to the drawings, particularly to Figs. 5, 6 and 7, the so-called snap clothes pin for which the machine is especially adapted is indicated at C and comprises two clamping members generally made of wood having handle portions a, b respectively, terminating at their opposite ends in jaw portions a', b' respectively, and a spring member S which secures the clamp-

ing members together intermediate their ends in such a manner as to form a fulcrum somewhat similar to a pair of pincers and at the same time holding the jaws yielding in engagement with each other. In this position the rear ends of the handles are spread apart but when the handles are pressed toward each other the jaw portions will be spread apart. The spring member is formed with a barrel portion d and with upper and lower leg portions e and f respectively. The upper arm e has an inwardly extending substantially lateral portion g which has a right angle bend at its free end to form a downwardly extending portion h. The lower arm f has a correspondingly inwardly extending lateral portion i which has a right angle bend at its free end to form an upwardly extending portion j.

Each handle member a, b has a substantially semi-circular cut-away portion or groove k on its inner side intermediate the ends corresponding to the curvature of the barrel portion of the spring. Between the cut-away portions or grooves k and the jaw each handle member is formed with a notch l on its outer side for the reception of the free ends h, j of the spring. The jaw members are formed with cooperating curved notches m, m to allow for the clothes line in well-known manner.

Before assembly, the spring member S appears as shown in Figs. 6 and 7 with the free ends h and j in engagement with each other. It is the object of this machine to assemble the parts by first spreading the free ends of the spring apart from each other and then feeding the clamping members forward to cause the handle portions a, b of the clamping members to enter between the spread free ends of the spring far enough for the cut-away or groove portions k of the clamping members to embrace the barrel portion of the spring at which time the free ends of the spring are permitted to snap toward each other and engage with the notches l in the outer sides of the clamping members.

Preferably, the machine is provided with means for automatically feeding the clamping members and the springs to the assembling mechanism. For convenience, the feed mechanism will be briefly described first. The two co-operating clamping members and the spring for each clothes pin all

have separate feeding mechanism. There are two hoppers 20, 21, for the clamping members, two rotary feed wheels 22, 23, respectively, to receive the clamping members 5 from the hoppers, and vertical chutes or guideways 24, 25, into which the said clamping members are delivered by the rotary feed wheels, the said clamping members sliding by gravity down the guideways into 10 proper relative position for the assembling operation. Preferably, a partition 96 is provided between the guideways 24, 25. This feed mechanism will be more particularly described hereinafter.

15 The feed mechanism for the springs consist of a vertical chute 26 having a guide way 27 into which the springs are fed to slide by gravity down onto a bed 28 where each spring in turn will be in proper position 20 for the assembling operation. A pin 29 normally projects up through an aperture in the bed 28 in alignment with the axis of the barrel of the spring and extends through the said barrel to hold the spring in position 25 on its bed during the spreading of the arms of the spring and the assembling of the clamping members with the spring. The springs should be so positioned when fed into the chute 26 that the axis of the barrel 30 *d* of the spring will be in alignment with the axis of the pin 29. The said pin is mounted on a slide member 30 vertically slideable in the bed 28 and means are provided for moving the slide to carry the pin down out of engagement 35 with the barrel of the spring after the parts are assembled to permit the removal of the assembled clothes pin. The mechanism for actuating the said slide 30 and pin 29 will be more particularly described hereinafter. Means are provided for spreading the two opposite arms of the spring preliminary to the insertion of the clamping members between said arms. The bed 28 is formed with a guide way 31 for the pin slide 30. The lower arm of the spring rests on the top of the bed and the barrel extends up above the bed. Side guides 32, 32 are provided to form a guide way 40 in which the clamping members are 45 moved in assembling them with the spring. In order to spread the fingers *h*, *j* of the spring, the arms *e*, *f* which are in different vertical planes flaring away from each other have to be moved toward each other, that is, 50 into vertical planes which are more nearly together, although the horizontal planes in which they move remain the same so that the vertical distance between the said arms *e*, *f*, remains the same. The said spreading means consist of two horizontally movable 55 spreader bars 34, 35, mounted respectively on slides 36, 37 movable in guideways in the bed of the machine in opposite directions to each other, the upper spreading member 34 being adapted to engage the upper arm *e* of

the spring, and the lower spreading member 35 being adapted to engage the lower arm *f* of the spring. Preferably the said spreader members are adjustable longitudinally on the slides 36, 37 to permit regulation of the extent of spreading action. This is accomplished by providing the spreaders with elongated slots 38, 38 and securing the spreaders to the slides by clamping screws 39 which pass through the said slots and into screw holes in the slides. The said spreaders should be adjusted so that they will have sufficient movement to spread the arms *e*, *f* of the spring a sufficient distance to permit entrance of the handles *a*, *b* of the clamping member. Recesses 3, 3 are formed in the side walls 32, 32 of the guideway 40 to receive the ends of the arms of the spring when they are spread apart.

The clamping members are discharged 85 from the lower ends of the vertical guideways 24, 25 into the horizontal guide way 40 in the bed of the machine. A slide member 42 is provided which is adapted to engage the rear ends of the jaw portions 90 *a*', *b*' of the clamping members to push the said clamping members along in the guide way and push the handle portions *a*, *b* in between the fingers *h*, *j* after they are spread apart. The slide first moves forward to 95 bring the curved notches *k*, *k* into alignment with the barrel of the spring and at the same time to bring the notches *l*, *l* into alignment with the vertical fingers *h*, *j* of the spring at which time the fingers *h*, *j*, will 100 snap into the notches *l*, *l* due to the tension of the spring, and the curved notches or grooves *k*, *k* of the clamping members will snap into engagement with the barrel *d* of the spring. The slide then moves forward 105 a short distance further to eject the assembled clothes pin.

Means are provided to actuate the pin-carrying slide 30, the spring spreading members 34 and 35 and the pusher slide 42 for the clamping members in proper timed 110 relation to each other. Any suitable means may be provided.

The particular means shown in the drawings is a series of cams 50, 51, 52 mounted on a drive shaft 4. The pin slide 30 is actuated by the rim cam 50 mounted on said shaft 4. A spring 5 is connected at its lower end to a collar 6 loose on the shaft 4 and is connected at its upper end to a pin 7 projecting from the slide 30. The said spring holds the lower end of the slide 30 in constant engagement with the periphery of the cam 50. The said cam is formed with a notch or depression 8 in its rim into which the lower end of the slide 30 will snap under the action of the spring 5 when during the rotation of the said cam the abrupt edge 9 of the notch comes around to the end of the slide. This will cause the slide to descend 125 130

and carry the pin 29 down out of engagement with the barrel of the spring so that the assembled clothes pin can be removed. As soon as said cam 50 has rotated far enough to bring the inclined end 10 of the depressed portion of the cam to the pin, the said pin will ride up on the inclined end 10 on the rim of the cam, and the slide and pin will be carried up into operative position ready to receive the barrel of the next spring.

The two slides 36, 37 which carry the spreaders 34, 35 are respectively actuated by the cams 51, 52 through intermediate mechanism as follows: A lever 53 fulcrumed at 54 carries on its lower arm a cam roll 55 which engages the rim of the cam 51 and is pivotally connected at its upper end at 56 with the slide 36. A tension spring 57 holds the cam roll 55 in engagement with the periphery of the cam.

When the cam roll 55 rides on the high part 58 of the cam the slide 36 is moved forward to cause the spreader bar 34 to engage and move the spring arm e. When the cam roll 55 rides off of the high part of the cam and on to the lower part 59, the spreader slide will be retracted by the spring 57.

A lever 60 fulcrumed at 61 carries on its lower arm a cam roll 62 which engages the rim of cam 52 and is pivotally connected at its upper end at 63 with the slide 37. A tension spring 64 holds the cam roll 62 in engagement with the periphery of the cam 52. When the cam roll 62 rides on the high part 65 of the cam 52 the slide 37 is moved forward to cause the spreader bar 35 to engage and push the spring arm f in the opposite direction to the movement of spring arm e. When the cam roll 62 rides off of the high part of said cam onto the lower part 66 the spreader slide will be retracted by the spring 64.

The slide member 42 for moving the clamping members into engagement with the spring S is actuated by an edge cam 67 on shaft 4 through intermediate mechanism as follows: A lever 68 fulcrumed at 69 carries at one end a roll 70 which engages the edge of the cam 67. The other end of said lever 68 is pivotally connected by a stud 71 with the outer end of a lever 72 fulcrumed at 73 to the frame of the machine. The inner end of said lever 72 is pivotally connected at 74 with the slide member 42. The fulcrum connection at 73 and pivotal connection at 74 are through elongated slots to allow proper movement of the lever. When the roll 70 rides on the high part 75 of the cam 67 the slide 42 is moved forward for the assembling operation. When the roll 70 rides off into the lower part 76 of the cam a tension spring 77 will retract the said slide.

It is important to have a dwell of the slide 42 after the parts are assembled and before

the additional forward movement to permit the pin 29 to be withdrawn from engagement with the spring. The cam 67 is formed with a flat place 78 to permit the dwell for this purpose.

The feed wheels 22, 23 are formed with pockets or grooves 80 extending transversely of the periphery of the wheels into which the blank clamping members will be delivered by gravity through the outlet in the bottom of the hopper. The attendant should see that the clamping members all lie parallel with each other in the hopper and with the handle ends all pointing in the same direction, so that when they pass down through the vertical guideways 24, 25 they will finally be delivered in the same relative position into the horizontal guideway 40 between the guides 32, 33 with the handle ends pointing toward the spring S as shown in Fig. 7. A doctor 81 is provided to throw any blank out of the pocket if, before it can be delivered to the chute, it is not in correct position. The doctor consists of a rotary member shaped something like a roll, mounted on a spindle 82 and having peripheral beads 83, 84 which are adapted to engage in the grooves k and m in the clamping member, if the clamping member blank is in proper position. In each case, the clamping member blank will ride 95 under the doctor without being disturbed.

If a clamping member is lying in incorrect position so that the grooves k, m do not register with the beads 83, 84, the blank will be knocked or kicked out of the pocket and back into the hopper again. Preferably the doctor or at least the beads, are of rubber so not to injure the blank. In order to provide a convenient means for keeping the chute 26 supplied with springs, I provide 100 separate holders onto which a plurality of springs may be strung and which may be positioned so that the springs may be automatically fed therefrom to the chute. A plurality of these filled holders may be kept 110 at hand so that the attendant may readily replace an empty holder by one of the filled ones. One suitable form of holder is shown in Fig. 1 of the drawings and is as follows:

It comprises a wire spindle or rod 85 secured to a holder member 86 and offset therefrom so that the springs can slide freely on the spindle without interference with the holder. The spindle is shown as being bent at its upper end to form an arm 87 by which it is secured to the holder 86. The holder 86 has secured thereto one leaf 88 of a hinge. A co-operating hinge member 89 is secured to the vertical chute 26 and has secured thereto a hinge pin 91. The hinge member 88 has a barrel member 92 which can readily be engaged with the hinge pin 91 by the attendant so as to connect the separable holder 86 with the vertical chute in such position that the springs strung on the wire spindle 130

85 will be fed into the upper end of the chute 26.

In order to retain the separable holder in position, a lever 11 is pivotally connected at 5 one end therewith, said lever being provided with a series of notches 93 adapted to be engaged with a pin 94 projecting from the frame. By providing a series of notches, the lever may be adjusted so as to position 10 the separable holder at varying angles of inclination if desired. It is preferable to have the holder at a slight angle of inclination with relation to the chute as shown.

A driving pulley 95 is shown on shaft 4. 15 Having thus described my invention, I claim:

1. In a machine of the character described, means for spreading the arms of the spring of a snap clothes pin, and means for feeding 20 the two clamping members of the clothes pin between the spread arms of the spring.

2. In a machine of the character described, means for spreading the arms of the spring of a snap clothes pin, means for feeding the 25 two clamping members of the clothes pin between the spread arms of the spring, and means for releasing the spreading pressure on the spring arms after the clamping members have entered between the said arms to 30 a predetermined position in relation thereto.

3. In a machine of the character described for assembling the clamping members of a snap clothes pin with a spring having an intermediate coiled portion and having its end 35 portions terminating in arms to engage the outer sides of the clamping members, means for spreading the arms of the spring to admit the two clamping members of the clothes pin between the spread arms, and means for feeding the said clamping members between 40 the spread arms of the spring.

4. In a machine of the character described for assembling the clamping members of a snap clothes pin with a spring having an intermediate coiled portion and having its end 45 portions terminating in arms to engage the outer sides of the clamping members, means for spreading the arms of the spring to admit the two clamping members of the clothes 50 pin between the spread arms, means for feeding the said clamping members between the spread arms of the spring, and means for releasing the spreading pressure on the spring arms after the clamping members have entered between the said arms to 55 a predetermined position in relation thereto.

5. In a machine of the character described for assembling the clamping members of a snap clothes pin with a spring having an intermediate coiled portion having its end 60 portions terminating in arms to engage the outer sides of the clamping members, and means for causing the arms of the spring to come into clamping engagement with the 65 outside of the clamping members of the pin

and to bring the coil portion of the spring in between the said clamping members of the pin.

6. In a machine of the character described, means for spreading the free ends of a coil 70 spring in which the coil forms an intermediate barrel portion terminating in arms at its free ends, and means for feeding between the spread arms of the spring two cooperating 75 clamping members of a clothes pin formed with notches to engage the said barrel and arms of the spring whereby the said arms and the barrel are permitted to snap into the notches in the clamping members.

7. In a machine of the character described, means for spreading the free ends of a coil spring in which the coil forms an intermediate barrel portion terminating in arms at its free ends, means for feeding between the spread arms of the spring two cooperating 85 clamping members of a clothes pin formed with notches to engage the said barrel and arms of the spring whereby the said arms and the barrel are permitted to snap 90 into the notches in the clamping members, and means for releasing the spreader mechanism from the spring after the said clamping members are assembled with the spring.

8. In a machine of the character described, means for spreading the free ends of a coil 95 spring in which the coil forms an intermediate barrel portion terminating in arms at its free ends, means for feeding between the spread arms of the spring two cooperating 100 clamping members of a clothes pin formed with notches to engage the said barrel and arms of the spring whereby the said arms and the barrel are permitted to snap into the notches in the clamping members, means for releasing the spreader mechanism 105 from the spring after the said clamping members are assembled with the spring, a reciprocal member which engages the barrel of the spring during the assembling 110 operation, and means for withdrawing said engaging member from the barrel after the parts are assembled.

9. In a machine of the character described, means for spreading the free ends of a coil 115 spring in which the coil forms an intermediate barrel portion terminating in arms at its free ends, means for feeding between the spread arms of the spring two cooperating 120 clamping members of a clothes pin formed with notches to engage the said barrel and arms of the spring whereby the said arms and barrel of the spring are permitted to snap into the notches in the clamping members, means for releasing the spreader mechanism 125 from the said spring after the said clamping members are assembled with the barrel of the spring during the assembling 130 operation, means for withdrawing the pin

after the parts are assembled, the actuating mechanisms for the spreading mechanism, for the feeding mechanism for the clamping members and the actuating mechanism for the reciprocable pin being all so timed with relation to each other that the said pin will be brought into engagement with the spring before the spreading members open the arms of the spring and will be retained in such engagement until the spring and arms are fully assembled and then will be withdrawn from engagement with the spring to permit the assembled clothes pin to be removed.

10. In a machine of the character described for assembling the clamping members of a snap clothes pin with a spring having an intermediate portion coiled in barrel form and having its end portions terminating in arms to engage the outer sides of the clamping members, a reciprocable member adapted to engage the barrel of the spring to hold it in position during the assembling operation, two oppositely disposed slide members adapted to engage the opposite arms of the spring and spread them apart from each other, a support for the two clamping members which holds them in alinement with the passage between the two arms of the spring, means for pushing the said clamping members in between the spread arms of the spring and then withdrawing, means for retracting the spreader members for the arms of the spring, and means for actuating said barrel engaging member, so timed that said member will engage the barrel of the spring before the clamping members and spring are assembled and then withdraw from engagement with the barrel of the spring.

40. 11. In a machine of the character described, two upright feed chutes adjacent each other for a pair of clamping members for a snap clothes pin, and a partition member between said feed chutes to maintain the two clamping members of each pair separated from each other during the passage thereof to the assembling mechanism.

12. In a machine of the character described, two hoppers for the clamping members of a snap clothes pin, two rotary feed wheels into which respectively the clamping members are delivered from said hoppers and two upright feed chutes into which the said clamping members are respectively delivered by the said feed wheels.

55. 13. In a machine of the character described, two hoppers for the clamping members of a snap clothes pin, two rotary feed wheels into which respectively the clamp-

ing members are delivered from said hoppers, two upright feed chutes into which the said clamping members are respectively delivered by the said feed wheels, said feed wheels being formed with pockets each of which is adapted to receive a single clamping member in a predetermined position to be delivered to the assembling mechanism and a doctor adjacent each feed wheel so disposed that it will throw out of the feed wheel any clamping member which does not lie in the pocket in the predetermined position.

14. In a machine of the character described, two hoppers for the clamping members of a snap clothes pin, two rotary feed wheels into which respectively the clamping members are delivered from said hoppers, two upright feed chutes into which the said clamping members are respectively delivered by the said feed wheels, said feed wheels being formed with pockets each of which is adapted to receive a single clamping member in a predetermined position to be delivered to the assembling mechanism and a doctor adjacent each feed wheel so disposed that it will throw out of the feed wheel any clamping member which does not lie in the pocket in the predetermined position, said doctor consisting of a rotary member having peripheral ribs adapted to engage with notches in the clamping member if the clamping member is in its predetermined position and thereby permit the said clamping member to ride past the doctor, said ribs being adapted to engage the clamping member in such manner as to throw it out of the feed wheel if the clamping member is not in its predetermined position to bring its notches in alinement with the said ribs.

15. In a machine of the character described, an upright feed chute for the springs of a snap clothes pin, said springs having an intermediate barrel portion formed by the coil of the spring, the ends of the springs terminating in arms, said feed chute having a guideway for the springs, in combination with a separable holder for a plurality of springs to be fed into said chute, said holder comprising a spindle on which a plurality of springs may be strung by engaging with the barrel thereof, and a holder for said spindle having means for detachably connecting the same with the machine in such position that the springs may slide by gravity from said spindle down into the guideway of the feed chute.

In testimony whereof I affix my signature.

SIMON S. TAINTER.
